DESIGN FOR A BROOCH OR SIMILAR ARTICLE OF JEWELRY

Harold Graeter, New York, N. Y., assignor to Cartier, Inc., New York, N. Y., a corporation of
New York

Application December 8, 1938, Serial No. 81,638

Term of patent 3½ years

To all whom it may concern:

Be it known that I, Harold Graeter, a citizen of the United States of America, residing at New York city, in the county and State of New York, have invented a new, original, and ornamental
Design for a Brooch or Similar Article of Jewelry,
of which the following is a specification, reference being had to the accompanying drawing, forming part thereof.

Figure 1 is a front elevation of a brooch or similar article of jewelry, showing my new design.

Figure 2 is a plan view of the article shown in Figure 1.

I claim:

The ornamental design for a brooch or similar article of jewelry, as shown.

HAROLD GRAETER.
